US00D614325S

(12) **United States Design Patent**
Mier-Langner et al.

(10) **Patent No.:** **US D614,325 S**
(45) **Date of Patent:** ** *Apr. 20, 2010

(54) **TRACK FIXTURE LUMINAIRE**

(75) Inventors: **Alejandro Mier-Langner**, Providence, RI (US); **James E. Kuchar**, Fall River, MA (US)

(73) Assignee: **Koninklijke Philips Electronics N.V.**, Eindhoven (NL)

(**) Term: **14 Years**

(21) Appl. No.: **29/317,777**

(22) Filed: **May 6, 2008**

(51) **LOC (9) Cl.** **26-05**

(52) **U.S. Cl.** **D26/26**

(58) **Field of Classification Search** D26/60,

(57) **CLAIM**

The ornamental design for a track fixture luminaire, as shown and described.

DESCRIPTION

FIG. 1 is a front perspective view of the track fixture luminaire of the present invention;

FIG. 2 is a left side view of the design of the present invention; the right side view is a mirror image of the left side view and is not shown;

FIG. 3 is a front view of the design of the present invention; FIG. 4 is a rear view of the design of the present invention; and,

FIG. 5 is a bottom view of the design of the present invention. The broken lines showing environmental structure are for illustrative purposes only and form no part of the claimed design.

1 Claim, 5 Drawing Sheets
